ILLUMINATED SIGN

Filed Dec. 29, 1927

2 Sheets-Sheet 2

Fig. 4.

Patented July 31, 1928.

UNITED STATES PATENT OFFICE.

JOHN W. WHISENANT, OF LOS GATOS, CALIFORNIA.

ILLUMINATED SIGN.

Application filed December 29, 1927. Serial No. 243,334.

This invention relates broadly to illuminated signs adapted to be used for display purposes in store display windows or wherever found desirable.

5 The main object of the invention is to provide a sign having parts arranged to reflect from a mirror a design thrown thereon by light rays passing through an opaque screen having parts made transparent to form the

10 desired design.

A further object is to provide a sign of the class mentioned having the design screen adjustable relative to its support and having a mirror adjustable relatively to said screen.

15 Another object of the invention is to provide a sign of this character which can be folded for convenience in handling during the erection thereof and for convenience in shipping.

20 Other objects of the invention will appear as the detailed description thereof proceeds.

In the drawing:—

Figure 1 is a perspective view of the sign with its parts in operative position;

25 Figure 2 is an end elevation of the sign as shown in Figure 1;

Figure 3 is a front elevation of the sign;

Figure 4 is a plan view of the sign;

30 Figure 5 is a vertical section of the sign taken on the line 5—5 of Figure 4.

Figure 6 is a fragmentary central transverse section, to a larger scale, of the design carrying frame taken on line 6—6 of Figure 4.

35 Figure 7 is a horizontal section on the line 7—7 of Figure 2.

Figure 8 is a fragmentary sectional elevation of the sign with its parts in closed position.

40 As shown in the drawing the sign comprises a supporting frame F having a back 1, sides 2 and 3, bottom 4 and top 5.

The upper part of the frame is provided with a front cover 6 provided with hooks 7 adapted to receive the ends of supporting chains 8 which may be attached wherever desired to support the frame. A lamp bulb 9 suitably secured to the cover 6 is arranged under a reflector 10 in order to direct the 45 light rays on to a design screen secured in a frame 11 secured by hinges 12 to cover 6.

Supporting rods 13 at each end of frame 11 have one of their ends pivotally connected to the hooks 7 and have their other ends pivoted to slides 14 mounted to slide in grooves 15 formed by substantially Z-shaped plates

16 and the flanges 17 and 18 of the frame 11. The upper face of frame 11 is provided with slots 19 in which the shanks of hooks 20 slide; and thumb screws 21 secure the slides 14 in desired adjusted positions on frame 11. By this arrangement the frame 11 can be adjusted and held in any desired position relative to the supporting frame F.

A design frame 22 is supported by flanges 18 in the recess formed by flanges 17 and 18, and, is detachably held in said recesses by any suitable means such as the turn buttons 23 rotatably fixed in the upper face of frame 11. Preferably the design or lettering of the sign is outlined on the lower face 24 of the design glass 25 and all the glass within this outline is maintained clear, while the remainder of the glass is coated to prevent the transmission of light therethrough. Preferably, I use a ruby glass having the upper surface 26 ornamenteally waved or beaded, and I prefer to blacken the under side 25, around the design outline, with black silver oxide. In order to protect the design, I may use a sheet 27 of glass or other suitable transparent material to prevent scratching or accidental removal of the silver oxide coating.

A frame 28 carrying a mirror 29 is connected to swing on frame 11 by hinges 30; and, in order to cut off objectionable side lights, the ends of frame 28 are connected to the ends of frame 11 by means of pleated arcuate end walls 31 designed to fold and unfold as frame 28 is adjusted toward or from frame 11. In order to hold the mirror frame 28 in any desired adjusted position relative to the frame 11, each end of these frames has pivoted thereto the toggle links 32 adapted to be locked in any position relative angular adjustment by means of the locking thumb nut 33.

It will be apparent from the drawing that the design and mirror frames may be folded into the supporting frame F when not in use, and in this form can be easily handled for erection or shipping purposes. The angle to which the design and mirror frames are adjusted will depend upon the relative location of the sign and the points from which it must be viewed; and of course, will depend upon the effect desired.

The black oxide or other coating on the lower smooth face of glass 25 constitutes a stencil and may be replaced by any suitable stencil plate having the design contour cut

out to permit the transmission of light therethrough from lamp 9 into the mirror 29, and thence by reflection at any desired angle to the view point of an observer at the front 5 of the frame. In this particular case the stencil is cut to form the word "Drugs"; but it is to be understood that any desired form of stencil with any preferred form of design cut therethrough can be substituted for the 10 stencil illustrated.

What I claim is:—

1. A sign comprising a support having a frame hinged thereto, a transparent plate in said frame, a stencil on one face of said plate, 15 a mirror adjustable angularly relative to said frame, and means for holding said frame in its angularly adjusted position.
2. A sign comprising a support, a transparent plate having a design stenciled thereon, means for adjusting said plate angularly relative to said support, a mirror angularly adjustable relative to said plate, and means for holding said mirror in its angularly adjusted position. 20
- 25 3. A sign comprising a support, a light extending from said support, a stenciled

transparent plate hinged to said support below said light, a mirror hinged below said plate, flexible light excluding means connecting the ends of said plate to the ends of said mirror, means for adjusting and holding said plate and mirror angularly with respect to said support. 30

4. A sign comprising a support, a frame hinged to said support, a stenciled design 35 plate detachably mounted in said frame, a mirror hinged to said frame, means for holding said mirror in any desired angular adjustment relative to said frame, means for angularly adjusting said frame and mirror simultaneously relative to said support, and means for locking the last named means in adjusted position. 40

5. A sign comprising a casing, a frame hinged to the upper part of said casing, a 45 stenciled design plate detachably mounted in said frame, means for angularly adjusting said frame and mirror relative to said casing, said mirror and frame being hinged together for housing in said casing. 50

In testimony whereof I affix my signature.
JOHN W. WHISENANT.
